PULSE MULTIPLEX SYSTEM EMPLOYING
FIXED PULSE-TIME DISPLACEMENT FOR
SIGNALINGEdmond M. Deloraine, New York, N. Y., assignor
to Federal Telephone and Radio Corporation,
New York, N. Y., a corporation of Delaware

Application October 4, 1943, Serial No. 504,881

8 Claims. (Cl. 179—15)

1

This invention relates to communication and signaling systems and more particularly to signaling systems adapted to operate with modulated impulse systems.

In communication systems heretofore proposed, such as in telephone systems at present in use, special signaling over the line often requires special equipment to be provided particularly at the terminals in order that the signals be transmitted over the voice frequency band without being interfered with by voice currents, alternately signals are transmitted below or above the voice frequency band and special equipment is required at the terminals to generate and receive the signal and at repeaters to by-pass and amplify these signals. Both systems involve a fairly large amount of equipment, expensive both in first cost and maintenance cost.

It is an object of my invention therefore, to provide a simple type of signaling system particularly adapted for use with modulated impulse energy and requiring a minimum of terminal equipment to effect the desired signal control.

It is a further object of my invention to provide means for producing a signal interval in a train of impulses normally used for transmission of intelligence to provide the desired signaling.

It is a further object of my invention to alter the pulses of a time and/or amplitude modulated impulse channel to define a signaling interval therein.

A better understanding of my invention and the objects and features thereof may be had from the particular description thereof, made with reference to the accompanying drawings, in which:

Fig. 1 illustrates a multiplex impulse communication system provided with signaling equipment in accordance with my invention;

Fig. 2 is a set of curves used in explaining the operation of the system of Fig. 1;

Fig. 3 is an illustration of a modified multiplex impulse transmission system using a different form of signaling in accordance with my invention; and

Fig. 4 is a curve used in explaining the operation of the system of Fig. 3.

Turning first to Fig. 1, a synchronizing source 10 is provided to synchronously control supervisory transmitter 11 and two other time modulated channels 12 and 13. Each of these transmission channels is of the type in which a train of impulses is supplied, the impulses being modulated either in time or amplitude to convey intelligence over a transmission line, such as shown at 14. The synchronizing source serves to oper-

2

ate properly in timed relation the transmitters 11, 12 and 13 producing interleaved pairs of impulses 1, 2 and 3, respectively, shown in Fig. 2. These impulses may be amplified in a repeater 15 which may be an ordinary pulse repeater. At the far end of line 14 the received pulses are applied to separate receivers 16, 17 and 18. These receivers are synchronized in operation from a synchronizing source 19, also coupled to line 14 so that the impulses of the corresponding channel, only, will be passed by the receiver for that channel. This synchronizing source may, for example, be of the type such as illustrated and described in the co-pending application of applicant and N. H. Young, Jr., entitled "Synchronizing circuit for multiplex pulse system," Serial No. 504,204, filed September 29, 1943. Alternatively, the system may be any desired time pulse modulation system, for example, such as described in Patent No. 2,262,838, to E. M. Deloraine and A. H. Reeves. In the output of each receiver is provided a line to the voice output circuits coupled over a condenser 24 and a signaling circuit coupled over condenser 20. The particular type of impulse communication system is not material to the invention and so is not shown in detail.

When it is desired to transmit a signal, such as a ringing signal, the pulses of the selected channel are suppressed for a period providing the desired signaling interval. This may be accomplished, for example, by push buttons 25, 26 and 27. Depression of any of these push buttons disconnects the corresponding transmitter from line 14 so that the channel impulses are not transmitted during the period at which the button is depressed. Consider that push button 25 has been depressed, then impulses 1 shown in dotted line in Fig. 2 will be suppressed and will not appear on line 14. At receiver 16 a wave such as shown at 60 is provided to combine with the normally received impulses of this channel so as to select the desired channel impulses for demodulation. This serves to permit only impulses 1 to pass while blocking the receiver for impulses 2 and 3. As an example of a suitable circuit, reference is made to the co-pending application of E. Labin and D. D. Grieg, Serial No. 488,183, filed May 24, 1943, now Patent No. 2,419,570, dated April 29, 1947.

However, since during the signaling interval, the impulses from 11 are suppressed, nothing will be selected at 16. Under normal operating conditions, the energy derived from impulses 1 at 16 are applied from the output of receiver 16 over condenser 20 to the grid of vacuum tube 21. This

energy maintains the tube in operation and energizes relay 22 which, in turn, serves to hold open its relay contacts 23. Upon cessation of signals, however, the tube 21 is no longer energized and permits relay 22 to release closing contacts 23. The closure of contacts 23 connects in circuit with a battery, a buzzer 29 which serves to produce the calling signal.

Similar circuit arrangements are provided in the output of each of the channels 1, 2, etc., if desired, so that any one of these channels may be signaled by operation of the corresponding push button.

It is clear that, if desired, instead of suppressing the impulses by opening the circuit, known forms of combining circuits may be provided in the output of each transmitter to suppress the impulses.

In Figs. 3 and 4 is shown an alternative signaling arrangement in which, instead of suppressing the impulses, a fixed direct current bias is given to the impulse producing device of a channel displacing the impulses by a fixed amount. In the present embodiment amplitude displacement is shown. Only transmitter 11 and receiver 16 are shown, the other transmitters and receivers being substantially duplicates of this circuit. At the transmitting end is provided a battery 35 or other direct current source which, by closure of switch 36, is connected to transmitter 11 serving to produce time displacement of the impulses transmitted from 11. These impulses are applied over line 14 and repeater 15 to the receiver 16 which may be the supervisory demodulator circuit. Under normal conditions, when switch 36 is open, the output of receiver 16 will be an alternating current varying at voice or other intelligence frequencies as shown at 70, Fig. 4.

When switch 36 is closed for signaling, voice frequencies generally will not be present and the output will be a substantially constant level direct current, as shown at 71 of Fig. 4. Directly connected to the output of receiver demodulator 16 is a vacuum tube 31 and an input resistor 30. Under normal intelligence transmission conditions, the output of receiver 16 will not cause sufficient drop in resistor 30 to operate tube 31. Upon arrival of a signaling impulse, however, a relatively strong constant D. C. will flow through resistor 30 causing sufficient drop therein to operate tube 31. Tube 31, upon operation, energizes relay 32 over a suitable time constant circuit 33 closing contacts 37 and connecting buzzer 34 in series with its battery. Thus, during the signaling interval defined by impulse 71, the buzzer will be operated.

It is clear that in place of a common direct current source such as shown in 35, a low frequency signaling source could be provided. In this case, however, a low pass filter would be required in the output of receiver 16 to separate this low frequency signaling energy from the voice frequencies.

It is further clear that repeaters 15, shown in Figs. 1 and 3 may be of any type normally passing impulse modulations since the signaling condition applied to the line does not, in any way, alter the character of the impulses to be repeated.

It should be clear to those skilled in the art also that ordinary ringing frequencies, such as 150 cycle energy, may be applied over the regular voice lines to the various transmitters to simply modulate the impulses in accordance with this ringing frequency. This system also presents great advantage over known types of ringing sys-

tems since it requires no special apparatus at the terminal stations or the repeaters to assure that the signaling energy is passed properly.

While the signaling energy has been described as a ringing frequency, it should be clear that signaling for any purpose such as for dialing, metering or other supervision may be accomplished in a similar manner, in accordance with my invention. Likewise, if desired, the direct current signaling of Fig. 3 may be applied simultaneously with the application of voice signals, the coupling condenser 24 in the voice line serving to block the direct current from the voice outputs. However, in general, the signaling will take place at times when no voice is being transmitted. Accordingly, the system, such as shown in Fig. 1, is readily applicable to these systems.

While I have described above the principles of my invention with references to other disclosures of specific apparatus, and particular modifications thereof, it is to be clearly understood that this description is made only by way of example and not as a limitation on the scope of my invention as set forth in the objects of my invention and the accompanying claims.

What is claimed is:

1. In an impulse transmission system wherein a train of impulses arranged in time spaced relation to one another and displaced in time from their normal positions in accordance with intelligence to be transmitted serves as a transmission carrier, a method of operating a signal controlled device over said carrier to indicate that a call is being made which comprises giving to said impulses a fixed modulating time displacement equivalent to a direct current impulse modulation to produce a modified signaling interval between discrete impulses of said train of impulses, receiving said train of impulses, and operating said signal controlled device in response to said modified signaling interval.

2. In an impulse transmission system wherein a train of impulses arranged in time spaced relation to one another and displaced in time from their normal positions in accordance with intelligence to be transmitted serves as a transmission carrier, a method of operating a signal controlled device over said carrier to indicate that a call is being made which comprises modulating the impulses of said carrier with a signal producing time displacements of said impulses at a rate outside the frequency range of the transmitted intelligence to provide a modified signalling interval between discrete impulses of said train of impulses, receiving said train of impulses, and operating said signal controlled device in response to said modified signal interval.

3. A signaling system for transmitting control signals over an intelligence conveying channel carrier comprised essentially of a train of impulses spaced apart in time and adapted to be displaced in time from their normal positions in accordance with the amplitude of intelligence to be transmitted, comprising means for producing and transmitting said train of impulses, signal means for modulating the displacement of the impulses of said train to produce a fixed displacement thereof corresponding to said control signals, receiver means for receiving said train of impulses, output means for the intelligence conveyed by said impulse train, and signal controlled means in the output of said receiver means responsive to said fixed displacement for producing a signal.

4. A signaling system according to claim 5

wherein said signal controlled means comprises a relay circuit and means in said relay circuit for discriminating between control signals and said intelligence.

5. A signaling system for transmitting control signals over an intelligence conveying channel carrier comprised essentially of a train of impulses spaced apart in time and adapted to be displaced in time from their normal positions in accordance with the amplitude of intelligence to be transmitted, comprising means for producing and transmitting said train of impulses, signal means for impressing a direct current of predetermined amplitude on the means for producing said impulses for a predetermined period defining a modified signal interval between discrete impulses of said train corresponding to said control signals, said direct current producing a fixed displacement of said impulses, receiver means for receiving said train of impulses, a demodulator in said receiver means for reproducing said intelligence and said direct current, and a signal controlled means comprising a relay means operative in response to said reproduced direct current.

6. In a multi-channel transmission system wherein each channel of the system comprises a train of impulses displaced in time in accordance with the intelligence to be transmitted, the impulses of each channel being spaced in time with respect to one another to enable separation, a signaling system for operating a signal controlled device over any selected channel to indicate a call, comprising transmitter means for each channel to produce and transmit a train of impulses, signal means for operating on said selected transmitter to produce a fixed displacement of the impulses from said selected transmitter, individual receivers for receiving said trains of impulses from the respective transmitters, signal responsive devices for each of said receivers, and means responsive to said fixed displacement to operate said signal device at the selected receiver.

7. In a multi-channel transmission system wherein each channel of the system comprises a train of impulses displaced in time in accordance with the intelligence to be transmitted, the impulses of each channel being spaced in time with respect to one another to enable separation, a signaling system for operating a signal controlled device over any selected channel to indicate a call, comprising a direct current source, transmitter means for each channel to produce and transmit a train of impulses, means for applying energy from said direct current source to said selected

transmitter to effect a constant time displacement of the impulses to provide a modified interval between discrete impulses of said train of impulses from said selected transmitter, individual receiv-

5 ers for receiving and translating said trains of impulses from the respective transmitters to reproduce said direct current, signal responsive devices for each of said receivers, and means responsive to said reproduced direct current to
10 operate said signal device at the selected receiver.

8. In an impulse transmission system wherein a train of impulses arranged in time spaced relation to one another and displaced in time from

15 their normal positions in accordance with intelligence to be transmitted serves as a transmission carrier including an impulse modulator and means for applying intelligence amplitude signals to said modulator to produce corresponding time displacement of the impulses; means for operat-

20 ing a signal control device over said carrier to indicate that a call is being made, comprising means for applying a direct current potential to said modulator to give to said impulses a fixed modulating time displacement to produce a modi-

modulating time displacement to produce a modified signalling interval between the received impulses of said train of impulses, means for receiving said train of impulses, and means for operating said signal control device in response to said fixed modulating time displacement.
